(57) **CLAIM**

The ornamental design for a cooking assistance appliance, as shown and described.

DESCRIPTION

FIG. 1 is a top perspective view of a cooking assistance appliance showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a top perspective view of the cooking assistance appliance of FIG. 1 according to another embodiment, showing my new design;

FIG. 9 is a front view thereof;

FIG. 10 is a rear view thereof;

FIG. 11 is a right side view thereof;

FIG. 12 is a left side view thereof;

FIG. 13 is a top view thereof; and,

FIG. 14 is a bottom view thereof.

Portions of the cooking assistance appliance are shown in broken lines. The broken lines form no part of the claimed design.

1 Claim, 14 Drawing Sheets
